UNITED STATES PATENT OFFICE.

EPHRAIM HARRINGTON, OF BOSTON, MASSACHUSETTS.

DESIGN FOR A BUTTON.

SPECIFICATION forming part of Design No. 20,517, dated February 10, 1891.

Application filed January 17, 1891. Serial No. 378,161. Term of patent 14 years.

To all whom it may concern:

Be it known that I, EPHRAIM HARRINGTON, of Boston, Massachusetts, have invented or originated a new Design for Buttons, of which 5 the following is a specification, reference being had to the accompanying drawings, in which—

Figure 1 is a top view of the button. Fig. 2 is a cross-section of the same on line 2 2, 10 Fig. 1.

The button has a plain back. Its face is surrounded by an annular raised rim *a*, within which are formed in the face lobe-shaped or approximately lobe-shaped depressions *b*, arranged symmetrically and concentrically around a small annular central raised rim *c*. 15 In two of the depressions *b* are stars *d*, which

are slightly in relief or elevated above the bottom of the depressions in which they are situated.

The leading feature of the design consists of the depressions *b*, arranged symmetrically and concentrically around the annular central raised rim *c* and within the outer inclosing raised rim *a*.

What I claim is—

The design for a button, as herein shown and set forth.

In testimony whereof I affix my signature in presence of two witnesses.

EPHRAIM HARRINGTON.
